SPEED-CONTROLLED ACTUATING DEVICE

Harry E. Sloan, Hartford, Conn., assignor to The Cushman Chuck Company, Hartford, Conn., a corporation of Connecticut

Application October 10, 1950, Serial No. 189,339

9 Claims. (Cl. 264—3)

1

The present invention relates in general to an automatic actuating-device and more especially to a speed-controlled actuating-device for automatically operating an electric switch or the like, of the type disclosed, but not claimed, in Patent No. 2,563,970, dated August 14, 1951.

An object of the invention is to provide a superior speed-controlled actuating-device.

A further object of the invention is to provide a superior speed-controlled actuating-device which is of simple, economical and dependable construction.

A still further object of the invention is to provide a superior speed-controlled actuating-device, the elements of which are so compactly arranged that the entire device occupies comparatively little space.

A still further object of the invention is to provide a superior speed-controlled actuating-device wherein centrifugal force is employed to activate the device from its normal position to its operating position and wherein gravitational force is employed to return the device from its operating position to its normal position.

Other objects and advantages will appear to those skilled in the art from the following, considered in conjunction with the accompanying drawings.

In the accompanying drawings, in which certain modes of carrying out the present invention are shown for illustrative purposes:

Fig. 1 is a vertical elevation in section of the speed-controlled device of this invention shown in its normal inoperative position;

Fig. 2 is a vertical side elevation in section of the speed-controlled actuating device on line 2—2 of Fig. 1;

Fig. 3 is a vertical elevation similar to Fig. 1, but showing the device in its operating position;

Fig. 4 is a plan elevation in section on line 4—4 of Fig. 1;

Fig. 5 is a plan elevation in section on line 5—5 of Fig. 1;

Fig. 6 is an end elevation in section of the rotor and actuating-plate on line 6—6 of Figure 1;

Fig. 7 is a perspective view of the rotor of the speed-controlled actuating-device; and

Fig. 8 is a vertical elevation in section of another form which the device may assume in accordance with the present invention.

Referring to the drawings, the latter show two forms of the invention, each form being used for the purpose of automatically actuating an element which, in this instance, is a limit-switch, but it will be understood that either or both forms of the invention may have other applications and that modifications of the specific embodiments of the invention shown herein are contemplated and included within the scope of the appended claims.

2

The showing of Figs. 1 through 7

The automatic speed-controlled device shown in Figs. 1 through 7 comprises, in the main, a casing indicated generally at 10 consisting of a substantially cup-shaped base-member 11 having a cover-member 12 which, in turn, is provided with a cap 13, the cup-shaped base-member, cover-member and cap all being formed of a suitable material such as, for example, cast iron, steel or the equivalent.

The base-member 11 is shown fixedly mounted on a frame-member 14 by means of a substantially-vertical sleeve-portion 15 of reduced cross section integral at its upper end with the bottom of the base-member, and provided at its lower end with a supporting-flange 16 which is adapted to be bolted or otherwise detachably secured to the frame-member 14.

Extending through the frame-member 14 and the flanged sleeve-portion 15 of the base-member into the bottom thereof, is an axial aperture 17 which is substantially concentric with the sleeve 15, the axial aperture 17 being provided at its upper end with a substantially concentric counterbore which constitutes a seat for supporting a ball bearing 19. A similar counterbore is provided in the axial aperture 17 at its intersection with the bottom face of the supporting-flange 16 for accommodating a ball bearing 21, which is adapted to be secured therein between the bottom of the supporting-flange and the upper face of the frame-member 14 on which the supporting-flange is secured.

In general, the base-member 11, cover-member 12 and cap 13 are substantially circular, as shown especially well in Figs. 4 and 5, the cover-member 12 being detachably secured on the upper edge of the cup-shaped base-member by fastening-means such as, for example, machine bolts, to form therewith a substantially-closed chamber 23.

Formed on the cover is an integral upstanding eccentric-boss provided with a substantially-vertical internally-threaded aperture 24 extending therethrough and substantially in alignment with the axial aperture 17 of the base-member, the internally-threaded aperture 24 of the cover being provided adjacent its upper end with a substantially-concentric cylindrical restriction 25, which forms an annular downwardly-facing shoulder at the upper end of the internally-threaded aperture 24. Threadedly secured in the lower portion of the latter is a spring-compression adjusting-bushing 26, the upper end of which is adapted normally to be spaced below the aforesaid downwardly-facing shoulder of the restricted portion 25 of the aperture, so as to provide an annular upwardly-facing shoulder for supporting the lower end of a helical compression spring, as hereinafter described.

Mounted on top of the boss of the cover 12 and offset from its vertical aperture 24, is a supporting-block 27 on which is supported an instrumentality to be actuated by the instant speed-controlled device. This instrumentality is, in the present instance, an electric switch 28. The switch-actuating button 29 of the switch 28 projects outwardly and substantially horizontally therefrom and is arranged in immediate juxtaposition to an adjustable button-actuating pin 30 which, in turn, projects substantially horizontally from the substantially-vertical arm 31 of a bell-crank lever pivotally mounted as at 32 on the aforesaid supporting-block 27 for pivotal movement in a substantially-vertical plane. The opposite arm 33 of the bell-crank lever projects outwardly substantially horizontally with respect to its vertical arm 31 and in a direction substantially opposite to the button-actuating pin 30 thereof; the outer end of the horizontal arm 33 of the bell-crank lever being provided with an enlargement 34 which is located substantially directly above the bushed aperture 24 of the cover.

Other elements of the improved speed-controlled actuating-device are the counterpoised actuating-plate or disc or driver indicated generally at 35 and a rotor indicated generally at 36.

The counterpoised actuating-plate 35 comprises, in general, a substantially disk-shaped member having a concentric boss upstanding from the center of its upper face and provided with a substantially-vertical internally-threaded aperture 38. The underside of the counterpoised actuating-plate 35 comprises a frusto-conical surface 39; the inclination of the surface 39 being outwardly and upwardly from a substantially-concentric clearance-recess 40 formed in the center of the underside of the actuating-plate.

The counterpoising-means for supporting the counterpoised actuating-plate comprises, in the main, a stem or shank 41, the lower end of which is threadedly engaged in the internally-threaded aperture 38 of the actuating-plate, the stem 41 being mounted for vertical axial movement in the spring-compression adjusting-bushing 26 of the cover. The upper end of the stem 41 projects above the upper end of the bushing and is surrounded by the previously mentioned helical compression spring 42 in the restricted portion 25 of the bushed aperture, the lower end of the coil spring 42 being seated on top of the bushing 26 for adjustment thereby. The upper end of the spring is adapted to bear against the underside of a collar 43 which is threadedly received by the shank of an actuator stud 45 that is, in turn, threadedly received in the upper end of the shank 41, the adjustable stud 45 being provided with a head 46 which is adapted to be engaged by the enlargement 34 of the bell-crank lever, as and for the purpose hereinafter described.

Engagement of the upper end of the spring 42 with the collar 43 of the stem 41 serves to resiliently support the actuating-plate 35 in the upper part of the closed chamber 23. By providing a spring 42 of predetermined compressive strength and adjusting its compression by means of the aforesaid bushing 26, the spring may be made to support a major portion of the weight of the actuating-plate, whereby only a force sufficient to overcome the residual weight of the actuating-plate, is required to lift or raise the actuating-plate from its lower or operating position as shown in Fig. 3, to its upper or inoperative position of Fig. 1. In effect, therefore, the actuating-plate is substantially counterbalanced.

The collar 43 is axially adjustable on the stud 45 relative to the upper stop surface of the eccentric-boss of the cover for limiting the downward movement of the actuating-plate by seating on the upper surface of the eccentric-boss in the manner shown in Fig. 3 and for the purpose hereinafter described.

In the preferred construction, the actuating-plate is held from rotating in the chamber 23 by means of an eccentric-pin 47 fixedly secured in substantially-vertical axially-aligned apertures of the cover and actuating-plate.

The rotor 36 of the speed-controlled actuating-device comprises a shaft 48 arranged to be rotatably supported in the ball bearings 19 and 21 respectively of the axial aperture 17 in the base-member, the lower end of the shaft being provided with a washer-and-nut assembly 49 adapted to engage with the ball bearing 21 to prevent the rotor-shaft 48 from moving upwardly in the bearings. Secured on the lower extremity of the shaft below the frame-member 14 is a driven member 50 which, in the present embodiment of the invention, comprises a frusto-conical member adapted to frictionally engage the frusto-conical face of a drive-member 51. Although friction-means is illustrated herein for driving the rotor, it will be understood that a toothed gear and pinion or equivalent drive-means, may be employed.

Formed on the upper end of the rotor-shaft 48 symmetrically thereof and extending substantially at right angles to its longitudinal axis, is a rotor-head 52 which comprises, by way of example, a substantially-rectangular metal block provided in its upper surface with two (more or less) roll-tracks or guideways 53-53 formed therein on opposite sides respectively of the axis of rotation of the rotor-head. As shown especially well in Fig. 7, each roll-track comprises a substantially-cylindrical bore drilled into one end of the rotor-head on an axis which is substantially coincident with the longitudinal axis of the rotor-head but inclined vertically at a slight angle relative thereto so that the bottom 54 of each roll-track slopes upwardly and outwardly from its inner blind end, as shown especially well in Fig. 1. Moreover, each cylindrical bore is adapted to intersect the upper face of the corresponding end of the rotor-head to form longitudinal slots or gaps therein having substantially-parallel edges or lips 55-55. The specific form of the roll-tracks 53-53 disclosed herein, and hereinabove described, are especially adapted to accommodate ball-like rolling-members 56, each ball-like rolling-member being a substantially solid-metal spherical ball, the diameter of which is only slightly less than the cylindrical bore of its respective roll-track so that the ball may roll freely therein, the movement of each ball being radial with respect to the axis of rotation of the rotor. Each ball 56 is effectively held from upward movement out of its respective roll-track by the lips 55-55 of its respective track. Moreover, each ball is effectively held from rolling out of the open end of its respective roll-track by means of a ball-retaining strap or yoke 59 secured across the corresponding end of the rotor-head. By reference to the drawings, it will be clear that a portion of the spherical surface of each ball projects out of its track above the upper face of the corresponding end of the rotor-head and is adapted thus to engage the aforesaid frusto-conical surface 39 of the actuating-plate. It will be noted that the angle of inclination of the up-

wardly-and-outwardly-sloping bottom wall 54 of each roll-track is slightly less than the angle of inclination of the upwardly-and-outwardly-sloping frusto-conical surface 39 of the actuating-plate. Thus, the vertical spacing between the bottom wall 54 of each roll-track and the frusto-conical surface of the actuating-plate increases from the inner end of each roll-track outwardly.

Thus, as the balls 56—56 roll up their respective inclined tracks outwardly of the rotor-head, the actuating-plate is permitted to drop downwardly relative to the rotor-head. On the other hand, as the balls roll inwardly down their respective inclined tracks, the balls serve to force the actuating-plate upwardly relative to the rotor-head.

As pointed out above, the roll-members shown in the present embodiment constitute balls, but it will be understood that the rolling-members may comprise cylindrical rollers, if desired, in which case, suitable tracks are provided in the rotor-head for guiding the radial movement of the cylindrical rollers. Moreover, although two rolling-members have been found to operate successfully, it is within the purview of the invention to use more than two balls or cylindrical rollers in the rotor-head for displacing the actuating-plate.

Operation of the showing of Figs. 1 through 7 inclusive

The speed-controlled device disclosed in Figs. 1 through 7 is adapted to automatically operate the exemplary electric switch 28 housed within the cap 13 of the device for energizing and de-energizing an electric circuit. Assuming, then, that the switch 28 is so arranged that it is normally held open, then on releasing its button 29, the switch will be closed. Conversely, upon re-engaging the button 29, the switch will be automatically opened. The actuation of the switch is effected as follows. When the rotor is stationary, the device may be said to be in its normal position wherein the actuating-plate is held upwardly in its raised position with respect to the rotor-head by engagement of the balls 56 with the inner peripheral edge of the upwardly-and-outwardly-sloping frusto-conical surface 39 of the actuating-plate. The weight supported by the balls is that fractional part of the weight of the actuating-plate which is not carried by the counterpoising spring and is hereinafter referred to as the residual weight of the actuating-plate. The shank 41 of the actuating-plate is likewise in its raised position, whereby the head 46 of the stud 45 supports the arm 33 of the bell-crank lever in a substantially-horizontal position in which the actuating-pin 30 of the bell-crank lever engages the button 29 of the switch to hold the latter open.

Upon rotation of the drive-member 51 and the driven pinion 50, the rotor-head will be rotated rapidly, whereupon centrifugal forces are developed which roll the balls outwardly and upwardly in their respective inclined roll-tracks. As the balls move outwardly, the actuating-plate is gradually lowered from its normal raised position to its lowermost or operating position, due to the slope-differential between the bottom wall of each track and the frusto-conical surface 39 of the actuating-plate, the actuating-plate being held in its lowermost position against further descent when the collar 43 becomes seated on the upper stop surface of the eccentric-boss, as shown in Fig. 3. By adjustment of the collar 43, the

actuating plate 35 may be adjusted vertically so that the same is, in its lowermost position, spaced slightly from the balls 56 when the latter are at or adjacent the outer ends of their respective tracks. Concurrently with the lowering of the actuating-plate 35, the head 46 of the stud 45 is lowered to permit the horizontal arm 33 of the bell-crank lever to swing downwardly in a counterclockwise direction as viewed in Fig. 1, and in so doing withdraws its holding-pin 30 from engagement with the button 29 of the switch, so as to permit the latter to automatically close.

Upon disengaging the rotor drive-means, the rotor gradually comes to rest, during which interval the centrifugal forces which hold the balls at their outer extremities of their respective tracks gradually diminish until the balls are no longer held thereby at the outer extremities of their respective tracks. Since the actuating-plate 35 is supported clear of the balls in the manner hereinabove described, the balls are unrestrained and hence gravitational force acting on the balls will cause the balls to start to roll back down their respective inclined tracks. After gaining some momentum, the balls will reengage the frusto-conical surface of the actuating-plate against which they exert a wedging action of sufficient force to overcome the residual weight of the actuating-plate and lift it upwardly to its normal position. Thus, when the balls arrive at the inner ends of their respective inclined tracks, the actuating-plate is fully elevated relative to the rotor-head and the horizontal arm of the bell-crank lever swung upwardly in a clockwise direction to its normal substantially-horizontal position, wherein its holding-pin 30 engages the button 29 of the switch to hold the latter open.

As previously mentioned, the bushing 26 may axially be adjusted to vary the compression of the spring 42 and thus permit ready fine adjustment of the counterbalance of the actuator plate 35. On the other hand, the collar 43 is axially adjustable to permit ready vertical adjustment of the actuator plate 35. Finally, the stud 45 is axially adjustable on the shank 41 of the actuator plate 35 so that the stud 45 may have its vertical stroke in the same region relative to the electric switch 28 even if the actuator plate 35 is vertically adjusted.

The showing of Fig. 8

In the showing of Fig. 8, certain of the parts correspond to those previously described herein and such parts have reference characters applied thereto which correspond to those previously employed.

In the embodiment of the invention shown in Fig. 8, all parts of the device are substantially identical to those shown and described hereinabove, with the exception of the actuating-plate which is indicated by the reference character 35a and provided on its underside with an outwardly-and-downwardly-inclined frusto-conical surface 39a. The upwardly-inclined bottom walls of the respective ball-tracks and the frusto-conical surface 39a immediately thereabove thus converge toward the outer ends thereof.

In accordance with this construction, the normal position of the actuating-plate is its lowermost position with respect to the rotor-head, in which position the actuating-plate is restrained by engagement of its adjustable collar 43 with the upper stop face of the eccentric-boss of the cover. Since in this form of the invention the forces acting on the balls to return them to their normal innermost positions are diminish-

ing as the balls approach their innermost positions, clearance is preferably provided between the frusto-conical surface of the actuating-plate and the balls, when the latter are in their normal inner positions by adjustment of the adjusting-nut 43, in the manner hereinabove described. As the balls are moved outwardly radially, they overcome the residual weight of the actuating-plate and elevate the latter into its operating position, as hereinafter described, in which position the balls will support the residual weight of the actuating-plate.

Assuming the actuating-plate is in its lowermost or normal position, then the head of the adjustable stud at the upper end of the shank 15 of the actuating-plate will be displaced downwardly below the horizontal position of the arm 33 of the bell-crank lever, whereby the latter is allowed to pivot counterclockwise and disengage its holding-pin from the switch-actuating button, thereby permitting the switch to close.

When the rotor is rotated, centrifugal force will carry the balls outwardly and upwardly along their respective inclined tracks, thereby raising the actuating-plate relative to the rotor-head due to the wedging action of the balls as they move outwardly between the upwardly-inclined bottom walls of the tracks and the downwardly-inclined frusto-conical surface of the actuating-plate. This upward movement of the actuating-plate elevates the head of the adjustable-screw of the actuating-plate to thereby pivot the bell-crank lever clockwise and, hence, move its holding-pin into engagement with the switch-button to hold the switch open.

Upon reaching the outer ends of their respective tracks, the balls are held from escaping therefrom by the yoke-members fastened across the ends thereof.

As explained above, as the balls arrive at the outer ends of their respective tracks, the residual weight of the actuating-plate is carried by the balls. Moreover, due to the inclination of the frusto-conical surface of the actuating-plate at its points of engagement with the balls, the residual weight or force of the actuating-plate tends to carry the balls back and downwardly along their respective tracks, thus augmenting gravitational forces acting on the balls.

Thus, when the rotor slows down and the centrifugal force acting to hold the balls at the outer ends of their respective tracks is diminished, a point will be reached at which the centrifugal forces are less than the combined forces of gravity and the residual weight of the actuating-plate acting on the balls to urge them back down their inclined ball-tracks, whereupon the balls roll downwardly and inwardly, thereby automatically lowering the actuating-plate back to its normal lowermost position with respect to the rotor-head. Inasmuch as both gravitational force and the residual weight of the actuating-plate act simultaneously on the balls to cause the latter to roll down their inclined tracks, this action may occur while the rotor-head is still rotating at an appreciable speed such as, for example, substantially 20 revolutions per minute.

On returning to its normal lowermost position with respect to the rotor-head, the actuating-plate carries the head of its adjustable-screw below the horizontal plane of the arm 33 of the bell-crank lever, whereupon the bell-crank lever pivots counterclockwise, thereby disengaging the switch-button and allowing the switch to close.

The speed-controlled actuating-device is thus 75

seen to embody relatively few moving parts, all of which are of durable, dependable and inexpensive construction and assembled in a compact manner to provide a device which occupies comparatively little space. Moreover, the device is characterized by its novel construction and arrangement of elements whereby centrifugal forces serve to actuate the device from its normal position to its operative position, while gravitational forces return the elements of the device to their normal inoperative positions.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A speed-responsive device, comprising a driver mounted for rotation about a substantially vertical axis and provided in its top with identical, substantially radially extending guideways terminating at their inner ends short of the rotary axis of said driver and having inwardly and downwardly inclined bottoms, respectively; identical balls received with a rolling fit in said guideways, respectively, and normally gravitating toward the respective inner ends thereof, said balls projecting above their respective guideways in any positions therein; a follower disc disposed above said driver in coaxial alignment therewith and being axially movable, said disc having a bottom surface riding on said balls and forming with the inclined bottoms of the adjacent guideways identical angles, respectively, so that said disc is raised and lowered on movement of said balls in opposite directions, respectively, in their respective guideways and will hinder gravitational inward movement of said balls in their respective guideways; and spring means partly counterbalancing said disc to permit said balls, despite the residual weight of said disc thereon, to gravitate toward the inner ends of their respective guideways as said driver comes to rest.

2. A speed-responsive device, comprising a driver mounted for rotation about a substantially vertical axis and provided in its top with identical, substantially radially extending guideways terminating at their inner ends short of the rotary axis of said driver and having inwardly and downwardly inclined bottoms, respectively; identical balls received with a rolling fit in said guideways, respectively, and normally gravitating toward the respective inner ends thereof, said balls projecting above their respective guideways in any positions therein; a follower disc disposed above said driver in coaxial alignment therewith and being axially movable, said disc having a bottom surface riding on said balls and being of such inverted conical shape that the same forms with the inclined bottom of each guideway an acute angle pointing inwardly toward the rotary axis of said driver, so that said disc is raised and lowered on inward and centrifugal outward movements, respectively, of said balls in their respective guideways; and spring means counterbalancing said disc sufficiently to permit said balls to gravitate toward the inner ends of their respective guideways and raise said disc as said driver comes to rest.

3. A speed-responsive device, comprising a

driver mounted for rotation about a substantially vertical axis and provided in its top with identical, substantially radially extending guideways terminating at their inner ends short of the rotary axis of said driver and having inwardly and downwardly inclined bottoms, respectively; identical balls received with a rolling fit in said guideways, respectively, and normally gravitating toward the respective inner ends thereof, said balls projecting above their respective guideways in any positions therein; a follower disc disposed above said driver in coaxial alignment therewith and having an upwardly extending coaxial shank; a fixed bushing through which said shank extends and in which it is guided for axial movement, said disc having a bottom surface riding on said balls and forming with the inclined bottoms of the adjacent guideways identical angles, respectively, so that said disc is raised and lowered on movement of said balls in opposite directions, respectively, in their respective guideways and will hinder gravitational inward movement of said balls in their respective guideways; a collar on said shank above said bushing; and a helical compression spring surrounding said shank and interposed between said collar and bushing, said spring partly counterbalancing said disc to permit said balls, despite the residual weight of said disc thereon, to gravitate toward the inner ends of their respective guideways as said driver comes to rest, and said collar is adjustable on said shank to permit axial adjustment of said disc.

4. A speed-responsive device as set forth in claim 3, further comprising an actuator stud threadedly received in the upper end of said shank so as to be axially adjustable thereon.

5. A speed-responsive device, comprising a driver mounted for rotation about a substantially vertical axis and provided in its top with identical, substantially radially extending guideways terminating at their inner ends short of the rotary axis of said driver and having inwardly and downwardly inclined bottoms, respectively; identical balls received with a rolling fit in said guideways, respectively, and normally gravitating toward the respective inner ends thereof, said balls projecting above their respective guideways in any positions therein; a follower disc disposed above said driver in coaxial alignment therewith and being axially movable, said disc having an upwardly extending coaxial shank and a bottom surface riding on said balls and being of such inverted conical shape that the same forms with the inclined bottom of each guideway an acute angle pointing inwardly toward the rotary axis of said driver so that said disc is raised and lowered on inward and centrifugal outward movements, respectively, of said balls in their respective guideways; a bushing through which said shank extends and in which it is guided for axial movement; a collar on said shank above said bushing; a stop above said bushing on which said collar will become seated on descent of said disc into a lowermost position in which the same will clear said balls only when the latter are substantially at the outer ends of their respective guideways; and a helical compression spring surrounding said shank and interposed between said bushing and collar, said spring being adapted to counterbalance said disc sufficiently to permit said balls to gravitate toward the inner ends of their respective guideways and raise said disc when said driver is substantially at rest.

6. A speed-responsive device as set forth in claim 5, in which said bushing is axially adjustable to vary the compression of said spring.
7. A speed-responsive device as set forth in claim 5, in which said collar is adjustable on said shank to permit axial adjustment of said disc.
8. A speed-responsive device as set forth in claim 5, in which said bushing is axially adjustable to vary the compression of said spring, and said collar is adjustable on said shank to permit axial adjustment of said disc.
9. A speed-responsive device, comprising a driver mounted for rotation about a substantially vertical axis and provided in its top with identical, substantially radially extending guideways terminating at their inner ends short of the rotary axis of said driver and having inwardly and downwardly inclined bottoms, respectively; identical balls received with a rolling fit in said guideways, respectively, and normally gravitating toward the respective inner ends thereof, said balls projecting above their respective guideways in any positions therein; a follower disc disposed above said driver in coaxial alignment therewith and being axially movable, said disc having an upwardly extending coaxial shank element and a bottom surface riding on said balls and being of such inverted conical shape that the same forms with the inclined bottom of each guideway an acute angle pointing inwardly toward the rotary axis of said driver so that said disc is raised and lowered on inward and centrifugal outward movements, respectively, of said balls in their respective guideways; a bushing through which said shank elements extends and in which it is guided for axial movement; an actuator stud element threadedly received in the upper end of said shank element so as to be axially adjustable thereon; a collar axially adjustable on one of said elements above said bushing; a stop above said bushing on which said collar will become seated on descent of said disc into a lowermost position in which the same will clear said balls only when the latter are substantially at the outer ends of their respective guideways; and a helical compression spring surrounding said shank and interposed between said bushing and collar, said spring being adapted to counterbalance said disc sufficiently to permit said balls to gravitate toward the inner ends of their respective guideways and raise said disc when said driver is substantially at rest.
